UNITED STATES PATENT OFFICE

114,970

DESIGN FOR AN ELECTRIC HAND SAW

Bolton Sullivan, Winnetka, Ill., assignor to Skil-saw, Inc., Chicago, Ill., a corporation of Delaware

Application April 1, 1938, Serial No. 76,217

Term of patent 14 years

To all whom it may concern:

Be it known that I, Bolton Sullivan, a citizen of the United States, residing at Winnetka, in the county of Cook and State of Illinois, have invented a new, original, and ornamental Design for an Electric Hand Saw, of which the following is a specification, reference being had to the accompanying drawing, forming a part thereof.

In the drawing:

Fig. 1 is a top plan view of an electric hand-saw showing my new design;

Fig. 2 is a side elevation thereof.

The dominant features of my design reside in the portions shown in full lines.

I claim:

The ornamental design for an electric hand saw, as shown and described.

BOLTON SULLIVAN.
